UNITED STATES PATENT OFFICE

95,479

DESIGN FOR LACE

Esther Alper, Brooklyn, N. Y.

Application February 1, 1935, Serial No. 55,192

Term of patent 3½ years

To all whom it may concern:

Be it known that I, Esther Alper, a citizen of the United States of America, and resident of the Borough of Brooklyn, county of Kings, city and State of New York, have invented a new, original, and ornamental Design for Lace, of which the following is a specification, reference being had to the accompanying drawing, forming a part thereof.

Figure 1 shows a plan view of a portion of the lace, showing my design, the dot and dash lines on the said figure defining the unit boundaries thereof.

Figure 2 is an enlarged edge view of Figure 1, the filled in areas of the fabric being accomplished by the irregular twisting of the crossing threads to form thickness, the crossing threads being substantially intermediate the thickness of the said filled-in areas, and the filled-in areas appearing substantially alike.

I claim:

The ornamental design for lace, as shown and described.

ESTHER ALPER.
